UNITED STATES PATENT OFFICE

EMIL C. ANDERSON, OF DOWNTONERS GROVE, ILLINOIS

CORRUGATED METALLIC WALL PLATE

Application filed March 15, 1928. Serial No. 261,897.

This invention relates to railway cars, and more particularly to wall structures therefor in which the side walls are designed to carry a part of the load to the body bolsters of the car and the end walls are designed to carry a part of the load to the side walls and to the draft sills, and the object of the invention is to provide a girder-wall for a railway car comprising a metallic plate (or plates) having certain elements formed integral therein, thereby eliminating the necessity of forming and fabricating such elements, thus reducing the number of parts and also reducing the weight of the finished car wall.

15 In the drawings:

Fig. 1 shows the side wall of a box car formed in accordance with my invention.

Fig. 2 is a section on line 2—2 of Fig. 1.

Fig. 3 shows a side wall of a box car with 20 a modified form of my invention applied thereto.

Fig. 4 is a section on line 4—4 of Fig. 3.

Fig. 5 is a modified form of Fig. 4.

Fig. 6 shows the relation of the chord, strut 25 and stiffener.

Figs. 1 and 2 show my invention used in the side wall of a railway box car wherein the side plate 2 and side sill 3 of the car are the upper and lower chords respectively of 30 the truss, and the "web plates" 4 form the retaining wall of the car. The integrally formed struts 5 of the truss form the transom post, intermediate post and door post respectively of the car, and the tie plates 6 or tension members of the truss form the usual "tie rods" between the sill and plate of the car. These tie plates 6 are preferably secured (7) 35 to the web plates 4 adjacent the sill and plate respectively. In this arrangement the web

40 plates not only form the retaining wall of the car but also constitute the gusset structure of the truss between the struts 5 and the chords and also between the tension members 6 and the chords. The reinforcing ribs 8 re- 45 tard the buckling tendency of the web plates

as gussets of the truss and also reinforce them to perform the functions of the retaining wall of the car. These ribs 8 may extend diagonally or horizontally but preferably extend vertically and parallel to the struts 5, as 50 shown, and preferably extend the distance between the chords and terminate within the web plates adjacent the chords so as to transmit any horizontal load imposed upon them by the lading to the chords. The tie plates 55 are preferably secured to the web plates between the reinforcing ribs so as to mutually reinforce both of them.

The integrally formed struts 5 overlap the sill 3 and plate 2 respectively, as shown in 60 Fig. 6, to enable them to act as compression members, and, furthermore, to better enable them to withstand the horizontal thrusts of the lading.

Figs. 3 and 4 show a modified construction 65 wherein the individual plates are connected along diagonal lines and the integral strut is formed parallel to the diagonal lines. This construction is used when it is desired to form a truss with compression members on diagonal 70 lines, as shown in Fig. 3, instead of on vertical lines, as shown in Fig. 1. The tension members are then preferably positioned vertically. The end diagonal pieces adjacent the corner post and door post respectively 75 need not necessarily be reinforced with stiffening corrugations.

Fig. 5 shows a modified construction where- 80 in the strut is formed adjacent one side of the individual plate and the adjacent plate is secured to the first mentioned plate on both sides of the strut, thereby forming a box gird- 85 er construction.

While I have shown the construction ap- 85 plied to a railway box car it is understood that it can be applied to gondola cars, hopper cars and any other form of railway car.

The accompanying drawings illustrate the preferred form of the invention, though it is to be understood that the invention is not 90

limited to the exact details of construction shown and described, as it is obvious that various modifications thereof within the scope of the claims will occur to persons skilled in 5 the art.

I claim:

1. A girder-wall for a railway car, comprising an upper chord, a lower chord, web plates with integral struts formed therein 10 which overlap said chords at their opposite ends, said plates also having integral stiffeners formed therein, and separate tension members having their opposite ends secured to said web plates adjacent said upper chord 15 and lower chord respectively.
2. A girder-wall for a railway car, comprising an upper chord, a lower chord, web plates with integral struts formed therein which overlap said chords at their opposite 20 ends, said plates also having integral stiffeners formed therein, and separate tension members having their opposite ends secured to said web plates adjacent said upper chord and lower chord respectively and also secured 25 to said web plates between said stiffeners.
3. A girder-wall for a railway car, comprising an upper chord, a lower chord, web plates with diagonal integral struts formed therein which overlap said chords at their 30 opposite ends, said plates also having integral stiffeners formed therein parallel to said struts, and separate tension members having their opposite ends secured to said web plates adjacent said upper chord and 35 lower chord respectively.
4. A girder-wall for a railway car, comprising an upper chord, a lower chord, web plates with integral struts formed therein which overlap said chords at their opposite 40 ends, said plates also having integral stiffeners formed therein to resist buckling stresses, and separate tension members tying the upper chord and lower chord together which are secured to said web plates.
5. A wall for a railway car, comprising a plate member, a sill member, and a plurality of plates connecting said members which are secured together near their adjacent edges, some of said plates formed with a relatively 45 deep corrugation which overlaps said members at its opposite ends and terminates with in the ends of the plate.
6. A wall for a railway car, comprising a plate member, a sill member, and a plurality 55 of plates connecting said members which are secured together near their adjacent edges, some of said plates formed with a relatively deep corrugation which overlaps said members at its opposite ends, each of said plates also formed with a plurality of relatively shallow corrugations which terminate within the plate between said members, and tie bars positioned angularly to said deeper corrugations and secured to the plate adjacent both of said members.
7. A wall for a railway car, comprising a plate member, a sill member, and a plurality 65 of plates connecting said members which are

secured together near their adjacent edges, some of said plates formed with a relatively deep corrugation which overlaps said members at its opposite ends and terminates within the ends of the plate, each of said plates also formed with a plurality of relatively shallow corrugations substantially parallel to the deeper corrugations which terminate within the plate between said members. 70

8. A wall for a railway car, comprising a plate member, a sill member, and a plurality of plates connecting said members which are secured together along diagonal lines near their adjacent edges, some of said plates formed with a relatively deep diagonal corrugation near one side of the plate and parallel thereto which overlaps said members at its opposite ends and terminates within the ends of the plate, each of said plates also formed with a plurality of relatively shallow corrugations substantially parallel to the deeper corrugations. 75

9. A wall for a railway car, comprising a plate member, a sill member, and a plurality of plates connecting said members which are secured together along diagonal lines, some of said plates formed with a relatively deep diagonal corrugation parallel to said lines which overlaps said members at its opposite ends and terminates within the ends of the plate, each of said plates also formed with a plurality of relatively shallow corrugations substantially parallel to the deeper corrugations which terminate within the plate between said members. 80

10. A wall for a railway car, comprising a plate member, a sill member, a plurality of plates connecting said members which are secured together near their adjacent edges, some of said plates formed with a relatively deep corrugation which overlaps said members at its opposite ends, each of said plates also formed with a plurality of relatively shallow corrugations which terminate within the plate between said members, and tie bars positioned angularly to said deeper corrugations and secured to the plate adjacent both of said members. 100

11. A wall for a railway car, comprising a plate member, a sill member, a plurality of plates connecting said members which are secured together near their adjacent edges, some of said plates formed with a relatively deep corrugation which overlaps said members at its opposite ends, each of said plates also formed with a plurality of relatively shallow corrugations which terminate within the plate between said members, and tie bars positioned angularly to said deeper corrugations and secured to the plate adjacent both of said members and between said shallow corrugations. 115

12. A wall for a railway car, comprising a plate member, a sill member, a plurality of plates connecting said members which are 120

130

secured together along diagonal lines near their adjacent edges, some of said plates formed with a relatively deep diagonal corrugation parallel to said lines which overlaps said members at its opposite ends, each of said plates also formed with a plurality of relatively shallow corrugations which terminate within the plate between said members, and vertical tie bars secured to the plate adjacent both of said members.
